US00D991679S

(12) United States Design Patent (10) Patent No.: US D991,679 S
(45) Date of Patent: * Jul. 11, 2023

(54) STORAGE BOX WITH LOCK

(71) Applicant: Guangzhou Mipi Car Accessories Co., Ltd., Guangzhou (CN)

(72) Inventor: Wenxiong Zheng, Guangzhou (CN)

() Term: 15 Years

(21) Appl. No.: 29/794,063

(22) Filed: Jun. 10, 2021

(30) Foreign Application Priority Data

May 26, 2021 (CN) 202130317748.5

(57) CLAIM

The ornamental design for a storage box with lock, as shown and described.

DESCRIPTION

FIG. 1 is a perspective view of a storage box with lock showing my new design;

FIG. 2 is a front view thereof;

FIG. 3 is a back view thereof;

FIG. 4 is a left- side view thereof;

FIG. 5 is a right- side view thereof;

FIG. 6 is a top view thereof; and,

FIG. 7 is a bottom view thereof.

The broken lines in the drawings depict portions of the storage box with lock that form no part of the claimed design.

1 Claim, 4 Drawing Sheets
